(57) **CLAIM**

The ornamental design for outsole for a shoe, as shown and described.

DESCRIPTION

FIG. 1 is a bottom perspective view of an outsole for a shoe showing my new design;

FIG. 2 is a bottom view thereof;

FIG. 3 is a left side view thereof;

FIG. 4 is a right side view thereof;

FIG. 5 is a front view thereof;

FIG. 6 is a rear view thereof; and,

FIG. 7 is an enlarged perspective view of the area labeled "7" in FIG. 1.

The broken lines shown in the arch area of FIGS. 1–2 represent boundaries of the design with the lines themselves and the areas within them forming no part of the claim. The crisscross broken lines shown in the forefoot and heel of FIGS. 1, 2, and 5 are included for the purpose of illustrating the portions of the sole that form no part of the claim.
